UNITED STATES PATENT OFFICE.

WILLIAM PRESTON HARTFORD, OF CASSVILLE, WISCONSIN, ASSIGNOR
OF TWO-THIRDS TO FRANK G. HORNBØGEN AND EDWIN SMEDLEY,
OF DUBUQUE, IOWA.

HOT-AIR FURNACE.

SPECIFICATION forming part of Letters Patent No. 689,078, dated December 17, 1901.

Application filed March 11, 1901. Serial No. 50,560. (No model.)

To all whom it may concern:

Be it known that I, WILLIAM PRESTON HARTFORD, physician, a citizen of the United States, residing at Cassville, in the county of Grant and State of Wisconsin, have invented 5 certain new and useful Improvements in Hot-Air Furnaces; and I do hereby declare the following to be a full, clear, and exact description of the invention, such as will enable 10 others skilled in the art to which it appertains to make and use the same.

My invention relates to a special construction of a hot-air heater or furnace and of its auxiliary devices. The action of the draft of 15 ordinary chimneys varies according to their size, height, and location and according to the velocity or direction of the wind, and this varying action of the wind will increase or decrease the draft, thus requiring constant 20 attention to change the dampers or to be changing frequently the direct draft and the indirect or check draft in order to prevent unnecessary consumption of fuel and to strive to keep the rooms at an even or de- 25 sired temperature. My invention does away entirely with this necessity of constant attendance, because my check-draft device hereinafter described acts automatically with 30 every variation in the action of the chimney-draft, as will presently be described.

In the accompanying drawings, Figure 1 is a longitudinal section through the brick-cased combustion-chamber, drum, check-draft, hot-air pipes, and by-pass. Fig. 2 is a 35 longitudinal section through the brickwork, showing the furnace and drum in position or not in section. Fig. 3 is a front elevation of a furnace bricked in. Fig. 4 is a foundation plan of the furnace bricked in. Fig. 5 is a 40 foundation plan of a furnace that is cased in with corrugated iron or steel sheets instead of with brickwork. Fig. 6 is a transverse section through a furnace cased in with corrugated-iron sheets. Fig. 7 is a front elevation of furnace cased with corrugated-iron 45 sheets.

Observe that the arrows (not feathered) indicate the direction of the heat and gases generated in the furnace, while the arrows having feathers thereon indicate the source and

direction of the fresh air passing around the furnace and around the superheating-drum on its way to the rooms of the building.

A is the combustion-chamber of the furnace, made of boiler-iron or steel that will not 55 crack, as do cast-iron furnaces.

B is the superheating-drum, made of thin wrought-iron or mild steel.

C is a rod that binds the drumheads to the drum. 60

d d d are eyebolts binding the furnace to the heads.

E is a by-pass cast in the head, as shown, and thereby doing away with the ordinary breeching. It spans an outlet at the inner 65 end of the furnace A and also an inlet at the same end of the drum B, and thus passes the products of combustion from the furnace to the drum.

fffff are the hot-air pipes, leading to the 70 rooms to be heated.

g g are the fresh-air pipes, leading in from outdoors or can be arranged to take air from a cellar. As shown, this cold air for circulat- 75 ing is entered directly under the fire-chamber and just where the heat is the greatest. This provision protects the furnace from being burned out at this point.

h is an inlet air-door beneath the chamber A to be used to admit cool air in warm weather. 80 As indicated by the feathered arrows, the route of cool air from h rises up outside the cylinders and also is free to pass up at the ends and around the by-pass and thence to the pipes fff, &c. 85

K is a direct-draft door located in the main door a', which door, as shown, covers the entire mouth of the furnace A to admit the largest logs. This door has a chain leading to an office or elsewhere for convenience. All 90 the ashes are readily removable from this mouth of A upon simply swinging open the main door a'. None can enter into the hot-air pipes nor into the rooms nor below the furnace. 95

L is an automatic check-draft on the drum B and having an adjustable counterbalance weight and lever m, that can be set to suit the side, height, or location of any chimney and according to the velocity or direction of 100

the wind and that will automatically open when the direct draft K is closed, as the action of the draft from the final outlet to the chimney will then be on the check-draft 5 door L, which, being nearly balanced, acts promptly, and when the direct draft K is opened again the action of the chimney being supplied again from the direct draft K the counterbalance m closes the door of the check-draft L.

N N are corrugated side sheets of a furnace. The object in using this type of sheet is that they will permit the cylinder and drum to expand and contract in heating and cooling, the shape of the sheets allowing them to come and go like a leather bellows.

O O O O O (see Figs. 1 and 2) are the top hot-air-pipe plates, arranged with lapped joints to prevent the escape of heat.

20 P is the final outlet to the chimney.

For convenience in cleaning the drum B the check-draft box is swung upon a pivot Q and lock (see Fig. 3) with an open jaw on collar-bolt R, which enables the operator to 25 swing it aside for cleaning, when it again drops into position from its own gravity.

From the above description it will now be seen that when fire is made in the furnace A, thus heating the furnace and the superheating-drum B, the hot air rushes to the top of the air-room surrounding the furnace and drum through the hot-air pipes f f f, &c. The vacuum thus created is filled by an influx of fresh air from any point desired, as 35 indicated by pipes g g and by dotted lines, (see Fig. 4,) leading in from any desired place, and that when the rooms are sufficiently heated the direct draft K being closed the check-draft L automatically opens, as stated above, 40 thus preventing the formation of creosote, which in ordinary constructions runs down

from the chimney into the furnace or stove, doing much damage, the check-draft L in my construction admitting enough fresh air to prevent this nuisance as well as saving fuel. 45 The by-pass E in the back plates displaces the breeching between two cylinders, which is always a weak and expensive feature. The combustion-chamber A has no bottom opening or grate nor any ash-box and is made 50 large and long enough to burn the longest cord-wood sticks without cutting. Both furnace and drum are made of wrought-iron or mild steel which will not crack, warp, or break. The corrugated side sheets are of a 55 character that will admit of expansion and contraction of furnace and drum without sustaining injury therefrom.

The entire apparatus is light, strong, and durable, and it is economical in the use of fuel 60 and can be made for one-third the usual cost of any other furnace known to me, bringing it within the reach of all, the entire cost being less than a good stove.

Having thus described my invention, I 65 claim—

A hot-air furnace adapted for burning uncut cord-wood, a combustion-cylinder and a superheating-cylinder both inclosed within a special furnace-wall composed of metal plates 70 at front and rear as shown broader than the cylinders, and of side sheets of corrugated metal secured to the ends of said plates, these sheets being thereby offset from the cylinders to leave open space between them and such 75 sheets, all as set forth.

In testimony whereof I affix my signature in presence of two witnesses.

WILLIAM PRESTON HARTFORD.
